UNITED STATES PATENT OFFICE.

JAMES V. GENOVESE, OF BREWSTER, NEW YORK.

SELF-WINDING SUSPENSION DEVICE.

1,084,623.

Specification of Letters Patent. Patented Jan. 20, 1914.

Application filed March 17, 1913. Serial No. 754,672.

To all whom it may concern:

Be it known that I, JAMES V. GENOVESE, a citizen of the United States, residing at Brewster, Putnam county, New York, have invented certain new and useful Improvements in Self-Winding Suspension Devices, of which the following is a full, clear, and exact description.

My invention relates to a new and improved self-winding suspension device which may be used to particular advantage for suspending such articles as chalk used for chalking the tips of billiard cues.

The object of the invention is to produce a very simple device of this character which may be easily manufactured and easily repaired without the exercise of any special skill.

In the drawings Figure 1 is a side elevation of my invention, the case being shown in section. Fig. 2 is a plan view thereof, the upper section of the case being removed. Fig. 3 is an end view of a detail. Fig. 4 is a view of detached details.

1—2 represent two hollow preferably hemispherical cover parts which are arranged to be detachably interlocked by any well known locking means, for example the well known bayonet joint lock, the stud parts of which are shown at 3—3 in Fig. 2. These studs are shown as carried by the lower case section 2, in which event the interlocking slots (not seen) for coöperation therewith would be formed on the other section 1.

4 is a spool preferably having flanges 5—5. The spool 4 is also provided, by preference, with an axle 6, the ends of which are detachably mounted in brackets 7—8, which may be carried by the part 2 of the casing.

40 The bracket 7 at its upper end is offset from the casing to form a holding shoulder or anchorage for the rubber band later described. The upper end of said bracket 7 is likewise turned forwardly toward the spool 4, and then downwardly, and is provided with a perforation 7^a to receive the adjacent end of the shaft 6, the extreme end of the shaft bearing for end thrust against the solid part of the bracket behind said perforated end. The bracket 8 is similarly constructed, excepting that in place of providing a perforation therein similar to 7^a, said bracket is provided with a slot 8^a, open at the top and into which the adjacent end of

55 the shaft 6 may be dropped, the end of the

shaft bearing against the solid part of the bracket back of the slot.

9 is a rubber band which is arranged as shown in the drawings, the ends of the band being slipped over the holding shoulders or anchorages formed by the offset parts of the brackets 7—8, the sides of the band lying in receiving grooves or notches 10—11 in the spool 4 to form holding shoulders.

12 is a cord, one end of which is attached in any suitable manner to said spool, the other end leading down through an opening in the bottom of the part 2 of the casing, which opening is preferably eyeleted or lined, as at 14, to prevent the abrasion of the cord 12 as it runs therethrough.

15 is a device by which the parts may be suspended.

16 represents the article supported by the cord 12, which in this instance may conventionally represent a holder for a piece of chalk.

To assemble the parts, the rubber band 9 is first placed longitudinally around the drum resting in the receiving grooves 10 and 11, the cord 12 is then secured to the drum and wound circumferentially around the same with only so much unwound as it is desired to have project from the case. The free end of the cord is then passed through the eyelet 14 in the lower section 2 of the case. The drum is then put into place with the axle 6 resting on the brackets 7—8. The exposed end of the rubber band is then stretched around the brackets 7 and 8, as best seen in Fig. 2. The upper section 1 of the casing is then coupled to the lower section 2 and the parts are ready for use. A downward pull on the cord 12 revolves the drum 4, winding up the rubber band 9. When the free end of the cord 12 is released, the rubber band 9 unwinds, revolving the spool so as to rewind the cord 12. Should the rubber band or cord break, the various parts may be easily separated and a new part inserted without the use of tools or the exercise of special skill.

The entire apparatus may be very easily and cheaply constructed and presents a handsome and finished appearance when in use. The brackets 7—8 which afford holding shoulders or anchorages for the band may, of course, be carried by either part of the case or housing, or, indeed, in any suitable manner. In some instances where only light

work is required, the axle 6 may be omitted, the rubber band itself affording a sufficient support for the spool 4. I would also regard a light coiled spring as the equivalent, in a broad sense, of the rubber band, although the latter possesses specific advantages such as compactness, cheapness, availability and noiselessness in operation. I shall therefore use the term "elastic band" 10 in the following claims as a term of sufficient breadth to cover the rubber band shown or any means substituted therefor.

What I claim is:

1. In a self-winding suspension device, a 15 revolute spool, an elastic band stretched longitudinally around the same, an anchorage for said band at each end of the spool but independent thereof, holding shoulders at each end of the spool for said band where- 20 by when the spool is revolved the ends of the band will not shift on said spool.
2. In a self-winding suspension device, a revolute spool, an elastic band stretched longitudinally around the same, an anchor-

age for said band at each end of the spool 25 but independent thereof, said spool having holding shoulders for said band whereby when said spool is revolved the ends of said band will not shift on said spool and an axle for said spool with supports for said 30 axle adjacent to the anchorages for said band.

3. In a self-winding suspension device for a revolute spool, an elastic band stretched longitudinally around the same, an anchorage for said band at each end of the spool but independent thereof, said spool having holding shoulders for said band whereby when said spool is revolved the ends of said band will be properly held on said spool, 40 an axle for said spool with supports for said axle adjacent to the anchorages for said band, and a cover for said parts, said cover affording a support for said anchorages.

JAMES V. GENOVESE.
